REFRIGERATING APPARATUS

Lawrence A. Philipp, Detroit, Mich., assignor to
 Kelvinator Corporation, Detroit, Mich., a corporation of Michigan

Application November 28, 1934, Serial No. 755,083

4 Claims. (Cl. 62—126)

This invention relates to refrigerating systems and particularly to refrigerating systems of the compressor-condenser-expander type.

Heretofore, in refrigerating systems of this type, it has been the practice to admit refrigerant into the evaporator at a single region, and frequently in such systems an even and uniform flow and distribution of the incoming refrigerant is not attainable, with the result that the proper circulation and agitation of the refrigerant in the evaporator cannot be obtained.

It is the principal object of the present invention to provide a refrigerating system in which the refrigerant is supplied to the evaporator below the liquid level in such a manner as to obtain a substantially uniform introduction of the incoming refrigerant into the evaporator and substantially uniform circulation throughout the area thereof to prevent the superheat of refrigerant in the evaporator.

Another object is to provide a refrigerating system in which the refrigerant is supplied to the evaporator below the refrigerant level and at a plurality of regions throughout the length of the evaporator rather than at a localized region as is the practice in refrigerating systems heretofore employed.

Other objects and advantages of the present invention will be apparent from the following description, reference being had to the accompanying drawing, wherein a preferred form of the present invention is clearly shown.

In the drawing:

Fig. 1 is a diagrammatic view of a refrigerating system, the evaporator thereof being enlarged and shown in section; and

Fig. 2 is a transverse section taken approximately on the line 2—2 of Fig. 1, showing the evaporator in detail.

Referring to the drawing, in which like numerals refer to like parts throughout the several views, I have shown in Fig. 1, for the purpose of illustration, a compressor-condenser-expander type of refrigerating system having an evaporator 10 and including a motor operated compressor unit 11, a condenser 12, a high side float type expansion valve 13 and a second expansion valve 14 connected by a high pressure conduit 15 with a valve 13, and also connected with the inlet of the evaporator 10.

Refrigerant vapor is withdrawn from the evaporator 10 through the vapor or low pressure conduit 16 leading to the compressor 11 and is liquefied in the condenser 12 and returned to the evaporator 10 through the liquid or high

pressure conduit 15. The valve 14 is pressure operated and keeps the pressure in conduit 15 sufficiently high enough to prevent the collection of frost and ice thereon.

The evaporator 10 comprises a pair of nested members A and B having spaced sides 17 and spaced bottoms 18 which provide side walls 19 and a bottom header 20, respectively, the top and end edges of the members A and B being continuously secured together to provide the refrigerant chamber within the evaporator which is composed of the walls 19 and bottom header 20.

The top portions of the sides 17 of the inner member A are preferably inwardly depressed to provide header spaces 21 which are placed in communication with each other by means of a transversely extending tubular upper header or manifold 22 welded at its ends to the sides 17 of the member A at the depressed portions thereof. The low pressure conduit 16 is connected with the upper header 22 by means of a suitable outlet connector 23.

The lower header 20 is provided with an inlet opening at one end, which receives an internally threaded inlet collar 24 into which a suitable connector 25 is threaded, the expansion valve 14 being connected with the inlet connector 25 as shown in Fig. 1.

As before stated, the present invention relates particularly to the manner of discharging the incoming expanded refrigerant into the evaporator 10, it being contemplated by the present invention to avoid the discharge of refrigerant at a localized region and to provide a means whereby the refrigerant will have a substantially even and uniform discharge into the evaporator along one side and throughout the length thereof, so as to obtain the proper circulation of the refrigerant within the evaporator.

In the form of the invention shown for illustration in Figs. 1 and 2, I have provided a distributing conduit 26 closed at one end and carried at the other end by the collar 24, so as to receive the incoming refrigerant from the expansion valve 14. This conduit extends substantially the full length of the lower header 20 between the spaced bottom walls 18 of the evaporator members A and B, and preferably substantially midway between the side walls 19 as indicated in Fig. 2.

The liquid refrigerant is discharged through a plurality of outlets 27 arranged on one side only of the conduit. These outlets provide a means whereby the incoming refrigerant will be discharged into the lower header at a plurality of

spaced regions, thus providing for a substantially even and uniform release of the refrigerant into the lower header 20 substantially throughout its length.

5 By discharging refrigerant from conduit 26 through outlets 27, which are positioned along one side of the conduit 26 only, the discharged refrigerant will flow in the direction of the arrows shown in Fig. 2. Thus, the refrigerant will 10 flow upwardly through side wall 19 on the right, as viewed in Fig. 2, whence it passes through header or manifold 22 into side wall 19 on the left and downwardly to the lower header 20 whence 15 it is recirculated in the same direction by the action of the incoming discharged refrigerant. Thus, the refrigerant entering the evaporator 10 is completely circulated throughout the evaporator and later is recirculated by the action of additional incoming refrigerant. Preferably, the 20 level of liquid refrigerant maintained in the evaporator 10 is at 29.

Preferably, the motor-compressor unit is intermittently operated and is controlled by an automatic switch 28 to which is connected a thermostat bulb 30. The bulb 30 is preferably secured to the evaporator, as shown in Fig. 2. Thus, the operation of the motor-compressor unit is controlled in response to changes in temperatures in the evaporator.

30 As shown in Fig. 2, the refrigerant outlets 27 in conduit 26 are positioned so as to discharge the refrigerant on the same side of the evaporator as the thermostat bulb 30 is positioned. Thus, the bulb 30 will be sensitive to the incoming refrigerant.

While I have shown the invention in the form of a conduit, it is to be understood that the same may assume any other suitable form which will provide for the discharge of the refrigerant into 40 the lower header at a plurality of spaced regions throughout its length. Also, any desired number of outlets may be provided in the conduit.

From the foregoing, it will readily be apparent that I have provided a new refrigerating system 45 wherein expanded (partly liquid and partly gas) refrigerant is introduced into the lower part of a refrigerant evaporator at a plurality of points in order to prevent the possibility of superheat of the refrigerant in the evaporator. By this arrangement, the expanded refrigerant upon entering the evaporator at a plurality of points will, upon rising to the upper headers, have a tendency to pick up stagnant liquid refrigerant located between the various points of introduction and 55 thereby cause the entire body of liquid to become stirred or agitated and circulated. This forced circulation and recirculation prevents substantially, if not entirely, the possibility of superheat of the refrigerant in the evaporator.

60 Although a single embodiment of the invention has been herein shown and described, it will be understood that numerous details of the construction shown may be altered or omitted without departing from the spirit of this invention 65 as defined in the following claims.

What I claim is:

1. A refrigerating system comprising an evaporator and a refrigerant liquefying unit operatively connected with said evaporator for circu-

lating a refrigerant therethrough, said evaporator comprising upper and lower headers, refrigerant containing side walls in open communication with each of said headers, a refrigerant distributing member within said lower header and having an inlet connected with said liquefying unit and having a plurality of spaced outlets for providing discharge of refrigerant into said lower header at spaced regions throughout the length thereof and toward one of said side walls only and a thermal element for controlling the operation of said liquefying unit and being responsive to changes in temperature in the aforesaid side wall to which the discharged refrigerant is first directed.

2. A refrigerating system comprising an evaporator and a refrigerant liquefying unit operatively connected with said evaporator for circulating a refrigerant therethrough, said evaporator comprising upper headers and a lower header, spaced side walls in communication with said headers, conduit means connecting said upper headers, and a refrigerant distributing member extending within and substantially throughout the length of said evaporator in said lower header, and having an inlet connected with said liquefying unit and a plurality of spaced outlets on one side only for providing discharge of refrigerant toward one of said upper headers whereby refrigerant will flow upwardly in one of said side walls to one of said headers and through said conduit means whence it will flow downwardly through another of said side walls.

3. A refrigerating system comprising an evaporator and a refrigerant liquefying unit operatively connected with said evaporator for circulating a refrigerant therethrough, said evaporator comprising upper and lower headers, two refrigerant containing side walls in open communication with each of said headers, and a refrigerant distributing member extending within and substantially throughout the length of said lower header substantially midway between said side walls, and having an inlet connected with said liquefying unit, and a plurality of spaced outlets for providing discharge of refrigerant into one side only of said lower header at spaced regions.

4. A refrigerating system comprising an evaporator and a refrigerant liquefying unit operatively connected with said evaporator for circulating a refrigerant therethrough, said evaporator comprising nested members having their sides and bottoms spaced apart to form a bottom header and spaced side walls and having their end and top edges continuously secured together, and a pair of top headers communicating with the upper portions of said side walls, conduit means interconnecting said top headers, said lower header having an inlet and a distributing conduit therein and connected with said inlet, said conduit being arranged longitudinally of said lower header and having a plurality of spaced outlets for providing discharge of refrigerant into said lower header at a plurality of spaced regions along one side only whereby refrigerant is circulated upwardly through one side wall to said top headers and downwardly through said other side wall to be recirculated.
